(57) **CLAIM**

The ornamental design for a display screen with transitional graphical user interface, as shown and described.

DESCRIPTION

FIG. 1 is a front view of a first image in a sequence of a display screen with transitional graphical user interface.

FIG. 2 is a front view of a second image in the sequence of the display screen with transitional graphical user interface.

FIG. 3 is a front view of a third image in the sequence of the display screen with transitional graphical user interface; and,

FIG. 4 is a front view of a fourth image in the sequence of the display screen with transitional graphical user interface. The appearance of the transitional graphical user interface of the is embodiment sequentially transitions between the images shown in FIGS. 1-4. The process or period in which one image transitions to another image forms no part of the claimed design. The broken line showing of the display screen is for the purpose of illustrating environment and forms no part of the claimed design.

FIG. 2

The screenshot shows the KPLCXUS software interface. At the top, there is a navigation bar with icons for search, refresh, and user profile. Below the navigation bar, the user's name, Nadia Harbeck, is displayed, along with her title, European Group on Tumor Markers (EGTM), and her location, Germany. There is also a 'View Powermap' button.

The main interface is divided into several sections:

- Overview:** This section contains a 'Personal Info' box and a 'Score Summary' box. The 'Personal Info' box lists 'Email' (No email information available), 'Phone' (No phone information available), and 'Addresses' (No address information available). The 'Score Summary' box shows a total score of 0.63/5, with breakdowns for expertise (0.5/5), publication record and citation experience (25%), regulatory and government experience (25%), and 'AsiaNet as a speaker' (0/5). It also lists 'Scientific interests And Capabilities' (0.8/5), including 'National research experience' (25%), 'Focus of clinical practice' (25%), and 'Focus of clinical practice' (25%).
- Research Activity:** This section contains a 'Upcoming Interactions' box with the message 'There are no upcoming interactions' and a 'Add New' button. It also contains an 'Upcoming Interactions' box with the message 'There are no upcoming interactions' and a 'Add New' button.
- Network:** This section contains an 'Affiliations' box with the message 'European Group On Tumor Markers (EGTM), Germany'.
- Events Calendar:** This section contains a box with the message 'There are no upcoming interactions' and a 'Add New' button.
